UNITED STATES PATENT OFFICE.

JULIUS YOUNG, OF SAN FRANCISCO, CALIFORNIA, ASSIGNOR TO CALIFORNIA CARD MANUFACTURING COMPANY, OF SAN FRANCISCO, CALIFORNIA, A CORPORATION OF CALIFORNIA.

EASEL MOUNTING FOR PHOTOGRAPHS AND THE LIKE.

Application filed July 18, 1923. Serial No. 652,463.

This invention relates to an easel mounting for photographs and the like and has for its object to provide a mounting of the character above indicated having means 5 which, when folded, will overlie and protect the photograph and which can be extended and interlocked to form a rigid easel support for the photographic frame whereby the latter will be displayed at the desired 10 angle.

One form which my invention may assume is exemplified in the following description and illustrated in the accompanying drawing, in which—

15 Fig. 1 shows a plan view of the mounting in open position.

Fig. 2 shows a side elevation of the same in interlocked position.

20 Fig. 3 shows a plan view of the mounting in folded position.

The present mounting comprises a central panel 10 provided with suitable means to receive and support a picture, photograph or the like. At the top of this central panel 25 is a second panel 11 joined thereto on a weakened line 12, so that it may be folded flat against the face of the picture, as indicated in Fig. 3, or may be swung back to form an inclined support, as shown in Fig. 30 2. Connected at the bottom of the central panel is a short panel 14 terminating in a flap 15. This bottom panel and flap can be folded over against the panel 11, as shown in Fig. 3, and in this position the pointed 35 end 15 of the flap is inserted in a slot beneath a tab 17 on the panel 11 for retaining the parts in folded position, thus wholly covering and protecting the photograph or picture on the central panel.

40 The other position of the bottom panel

14 is shown in Fig. 2, where it will be seen that it forms a base for the easel support and the flap 15 is inserted in a pocket in the back panel 11 and held therein by the plies 18.

45 Such a mounting as shown herein costs very little, if any, more than the ordinary foldable mounting, and has the further advantage of being quickly and easily set up to provide an easel support for a picture or 50 photograph carried by the central panel or frame. When so set up the picture frame or central panel is rigidly supported and held at the desired angle for properly displaying the picture.

55 Having thus described my invention, what I claim and desire to secure by Letters Patent is:

A mounting for photographs and the like, comprising an intermediate panel forming 60 a frame for the photograph, a panel hinged to the upper end of the intermediate panel and movable from a position overlying the front thereof to a position behind the intermediate panel, whereby to constitute one 65 leg of an easel, a short panel hinged at the lower end of the intermediate panel and movable from a position overlying the other end panel to a position where it will form a base for the easel, and means for interlocking said end panels both in folded and 70 extended positions, said interlocking means comprising a tongue hinged to the end of the short panel, a pocket in the free end of the opposite end panel formed by separating the plies thereof to receive said tongue when the parts are extended, and a tab on said last-named panel, beneath which said tongue is adapted to lie when the parts are folded.

75 JULIUS YOUNG.
